United States Patent Office.

B. L. FAHNESTOCK, OF PITTSBURG, PENNSYLVANIA.

Design No. 3,156, dated August 11, 1868.

DESIGN FOR TRADE-MARK.

The Schedule referred to in these Letters Patent and making part of the same.

TO ALL WHOM IT MAY CONCERN:

Be it known that I, B. L. FAHNESTOCK, of the city of Pittsburg, county of Allegheny, in the State of Pennsylvania, have originated a new Design for a Trade-Mark, of which the following is a full, clear, and exact description, reference being had to the accompanying specimens, making part of this specification.

a represents a circle, inside of which are other concentric ones, *d*. Radiating from the centre of these circles are four arms, *b*, widening as they go outward, and extending beyond the circle *a*. In the centre of *a*, and covering the inner ends of arms *b*, is a square, *e*, with the words "Trade-Mark" inside, the former being over the latter. There is a circle, *f*, inscribed at the outer end of each arm, there being inside of each, respectively, "B. L. F. & Co." Between the circles *a* and *d* and the arms *b*, are the words "Iron City White-Lead Works."

What I claim as my invention, and desire to secure by Letters Patent, is—

The design for a trade-mark, herein set forth and shown.

B. L. FAHNESTOCK.
